UNITED STATES PATENT OFFICE.

JOHN GEO. SAUER, OF ROCHESTER, NEW YORK.

LIFTING-JACK.

1,393,247.

Specification of Letters Patent.

Patented Oct. 11, 1921.

Application filed February 18, 1920. Serial No. 359,500.

To all whom it may concern:

Be it known that I, JOHN G. SAUER, a citizen of the United States, and resident of Rochester, in the county of Monroe and 5 State of New York, have invented certain new and useful Improvements in Lifting-Jacks, of which the following is a specification.

The present invention relates to lifting jacks, and an object thereof is to provide a lifting jack which has strength and durability and at the same time a maximum amount of power. Another object of the invention is to provide an improved lifting 15 jack which has a quick adjusting mechanism, permitting the lifting member to be engaged with the article to be lifted and a slow or power elevating mechanism which will permit the operation of the lifting member 20 after such engagement. A further object of the invention is to provide a lifting jack which may be operated from the rear thereof or from either side.

To these and other ends, the invention 25 consists of certain parts and combinations of parts all of which will be hereinafter described, the novel features being pointed out in the appended claims.

In the drawings:

30 Figure 1 is an end view section of the jack in elevated position;

Fig. 2 is a central vertical section of such jack in the position shown in Fig. 1;

Fig. 3 is a side view of the jack in lowered 35 position;

Fig. 4 is a fragmentary detail view of the connection between the base and the lower links of one of the toggles;

Fig. 5 is a fragmentary detail view of a 40 knuckle of a toggle of the rough adjusting mechanism;

Fig. 6 is a detail view of the connection between the lifting member and one of its toggles;

45 Figs. 7 and 8 are detail views of the connection between two of the weighted pawls;

Figs. 9 and 10 are detail views of the operating member for the jack; and

Fig. 11 is a detail view of the ratchet.

50 In the illustrated embodiment of the invention there is provided a lifting bar formed in this instance of two pieces of angle iron 1 connected together by tie pieces 1^a, each having one of its flanges disposed outwardly and horizontally and supporting a casting 2 preferably formed with intersect-

ing V-shaped notches 3 and 4, the casting 2 being preferably detachably secured at 5 to the flanges by bolts, dowel pins or other means. This bar is, in this instance, adjustably supported on a supporting frame comprising preferably two plates 6 connected together by tie pieces 7.

The adjusting means for moving the lifting member relatively to the supporting frame in the illustrated embodiment comprises a pair of toggles, each toggle being formed of two pairs of links, the lower links 8 of each toggle being pivotally mounted on pivot rods 9 connecting the plates 6, while the upper links 10 of each toggle are pivotally mounted on pivot rods 11 connecting the angle irons 1 and held thereon by nuts 11^a. The links 8 and 10 of each toggle are preferably pivotally connected to a knuckle 75 pin 12 on which the links are held by nuts 13. Movement of the toggles may be effected by an adjusting shaft 14 which may have right and left hand threaded portions 15 and 16 engaging in screw threaded openings formed 80 in the knuckle pins 12 of the two toggles, and rotation of this screw in one direction breaks the toggles by moving them toward each other, thus lowering the lifting bar, while movement of the screw in the other 85 direction expands the toggles and elevates the lifting bar. One end of the adjusting member may be provided with a head 17 having a squared socket in which a wrench may be fitted in line with the adjusting member. 90

To the end that the wrench may be used at right angles to the adjusting member, a socket member 18 may be provided having sockets in opposite faces thereof, and rotatable in bearings 19 about an axis at right 95 angles to the axis of the adjusting member 14. This socket member is, in this instance, formed with a worm face 20 which co-operates with a worm face 21 on the socketed head 17 of the adjusting member 14. The 100 bearings 19 are provided in a two part frame 22 which is secured about the adjusting member 14 between the head 17 and a collar 23 thereon by screws 22^a.

The supporting frame formed by the plates 105 6 may in turn be adjustably supported on a base 24, in this instance, in the form of a channel member with the side flanges 25 of the chamber presented upwardly. The adjusting means between the base member and 110 the intermediate supporting frame formed by the plates 6 is so constructed that a quick

adjustment may be obtained. Preferably this is secured by providing two toggles between the base 24 and the intermediate supporting frame. Each toggle has its lower member formed of four links 26 arranged in two pairs on a pivot rod 27, a spacer 28 being provided between the members of each pair and nuts 29 being arranged between the two pairs to secure the links against movement on the pivot rod 27. The upper member of each toggle is also formed of four links indicated at 30, said links being pivotally mounted on a pivot rod 9 on which the links 8 are pivoted and being arranged in two pairs with spacers 31 between them, the links 8 being arranged between the two pairs and nuts 32 being arranged to hold the links 8 as well as the links 30 against movement on the pivot rod 9. The two parts of each toggle have their links pivotally connected to a pivot rod 33, spacers 34 being provided on the pivot rod between each pair of links 30, and each pair of links 30 being arranged on the pivot rod 33 between the members of a pair of links 26. A spacer 35 is also provided on the pivot rod 33 between the two pairs of links 26, and nuts 35 secure the parts in operative relation. To elevate the intermediate frame formed by the plate 6 with reference to the base 24, the intermediate frame is raised and the links 26 and 30 automatically swing on their pivot until the desired height of the intermediate frame is reached.

In order to secure the intermediate frame in its adjusted position, a plurality of pawls 36 are provided, said pawls being pivoted at 37 on lugs 38 which are projected inwardly from the links 26, each pawl being pivoted to both members of each pair of links 26 and operating between such members so as to co-operate with ratchet teeth 39 formed on the spacers 34, such spacers 34 being keyed to the pivot pins 33 and said pivot pins in turn being keyed to the links 30. Each pawl is provided with a weight 40 which normally tends to hold such pawl in co-operation with its ratchet 39 so that, as the intermediate frame formed by the plate 6 is raised, the pawl will automatically lock the intermediate frame in its raised position. Release of the pawls may be secured by chains 41 which are connected at 42 to a tie-piece 7 between the plates 6 and which have their other ends connected with yokes 43 and 43^a, each of said yokes connecting two of the weights 40. The opposite weights 40 are offset so that they may lie one beside the other when the jack is folded. Links 44 may be provided on the connections 41 for attachment to hooks 45 arranged on the inner faces of the strips 6 to hold said weights in positions where the pawls 36 will be out of co-operation with the ratchets 39.

The operation of the screw 14 may be ef-

fected by an operating tool comprising, in this instance, an extensible stem formed of a plurality of telescoping sections 46, connection between the sections being provided by forming longitudinal slots 47 and inwardly turned lugs 48 on some of the sections, the lugs extending into said slots and permitting the relative longitudinal movement of the sections, while preventing relative rotary movement. A handle 49 is provided at one end of the tool, while a head 50 is provided at the opposite end and is formed with a squared portion for fitting in the sockets of the head 17 and the member 18. The head 50 has a universal connection 51 with the stem of the tool permitting the head to rock on the stem.

In the use of the jack, the latter is first operated to bring the lifting bar or member as close as possible to the intermediate support formed by the plates 6, while the intermediate support is brought as closely as possible to the base 24. The jack is placed beneath the part to be elevated, and the intermediate support formed by the plate 6 is raised until the lifting bar engages with the part to be elevated, at which time the pawls 36 will lock the rough adjusting mechanism in its adjusting position. The operating tool illustrated in Figs. 9 and 10 is then connected to the socket member 18 or to the socket member 17, depending on which is most conveniently reached, and the screw 14 is turned to elevate the lifting bar and the part engaged thereby until the desired elevation has been reached. In lowering the jack, the screw 14 may be turned or the jack may be lowered quickly by disengaging the pawls 36 with the ratchets 39.

From the foregoing it will be seen that there has been provided a lifting jack formed with a rough adjusting mechanism and a power adjustment. The rough adjustment may be quickly obtained, while the power adjustment gives great power. Both the adjusting mechanisms are simple in operation and have great durability and strength. Provision is made by which the jack may be operated from any side.

What I claim as my invention and desire to secure by Letters Patent is:—

1. In a lifting jack, a lifting member formed of two angle irons arranged in spaced relation, each having a flange projecting outwardly in a plane with the outwardly projecting flange of the other member, a supporting frame, a toggle connecting the supporting frame with the lifting member, and a block detachably secured to the flanges of the lifting member and formed with intersecting notches.

2. A lifting jack comprising a supporting member, a lifting member adjustably supported on said supporting member, a horizontally arranged screw for operating the

lifting member with reference to the supporting member, said screw having an operating portion at one end, and an auxiliary operating member for the screw operable 5 from either side of said screw at an angle to the axis of the screw and geared to the screw to transmit motion thereto.

3. A lifting jack comprising a base, a lifting member, a supporting member between 10 the base and the lifting member, toggles connecting the base and the supporting member, and toggles connecting the supporting member and the lifting member.

4. A lifting jack comprising a base, a lifting member, a supporting member between 15 the base and the lifting member, two quick adjustable toggles connecting the base with the supporting member, and power adjusting means between the supporting member 20 and the lifting member.

5. A lifting jack comprising a base, a lifting member, a supporting member between the base and the lifting member, adjusting

means between the supporting member and the lifting member, a toggle between the 25 base and the supporting member, and a pawl and ratchet controlling the position of the toggle.

6. A lifting jack comprising a lifting member, a base, a supporting member, adjusting means connecting the supporting member with the lifting member, a toggle connecting the base with the supporting member and having a tooth member at its knuckle, and a weighted pawl coöperating 35 with said tooth member.

7. A lifting jack comprising a lifting member, a supporting frame on which the lifting member is adjustable comprising two plates, pivot rods connecting said plates, a 40 base formed from a channel member with its flanges extending upwardly, pivot rods connecting said channel members, and two toggles mounted on the pivot rods of the supporting frame and the base.

JOHN GEO. SAUER.
